ELECTRIC CABLE COUPLER

Anthony D. Marasco, Norwalk, Conn., assignor to J. B. Nottingham & Co., Inc., New York, N.Y., a corporation of New York

Application February 13, 1958, Serial No. 715,041

23 Claims. (Cl. 200—51.09)

This invention relates to improvements in electric wire or cable coupling or connecting means.

In many areas where electrical equipment is used, such as industrial plants, chemical laboratories, etc., fumes or gases of easily ignitable character are frequently present which requires the exercise of extreme care in the use of such equipment to avoid the formation of sparks which might ignite such fumes or gases. Such spark formation is particularly likely to occur in connection with the use of plugs and sockets for electrically connecting machines or equipment to a source of current.

Further, in the use of hand held or manipulated electrical machines, or in the use of machines where an operator or attendant may have bodily contact therewith, the grounding of the machine as a safety measure is important and this is especially true if such machines are used in damp locations.

It is a particular object of the present invention, in view of the foregoing, to provide, in a manner as herein-after more particularly set forth, a new coupling or connector for joining electric current conductors, which can be made and/or broken without producing open or exposed sparks.

Another object of the invention is to provide, in the manner as hereinafter set forth, a new coupling or connector of the character stated wherein grounding contacts are joined one with the other before the actual closing of relatively movable current transferring contacts is effected.

Still another object of the invention is to provide a new plug and socket type coupler which is so designed that at least two manipulating acts are required to be performed in joining the plug and socket to effect closing of pairs of current conducting contacts in the socket part after electrically connecting each of two or more plug carried terminals with a cold one of a pair of contacts and wherein each pair of contacts is enclosed in a liquid and gas tight envelope, at least a part of the wall of which is elastic.

A still further object of the invention is to provide a new plug and socket type coupler wherein means is provided for locking the plug in the socket against direct axial withdrawal concurrently with the act of effecting electrical coupling of the enveloped pairs of contacts.

Still another object of the invention is to provide a coupler of the character described and by which to attain the hereinbefore stated objects, which is designed to effect the electrical joining together of grounding terminals in advance of the completion of the second act resulting in the electrical coupling of the enveloped pairs of contacts and while the plug carried terminals are electrically joined to the cold contacts of said pairs.

Other objects and advantages of the invention will become apparent as the description of the same proceeds and the invention will be best understood from a consideration of the following detail description taken in

2

connection with the accompanying drawings forming part of the specification, with the understanding, however, that the invention is not confined to a strict conformity with the showing of the drawings but may be changed or modified so long as such changes or modifications mark no material departure from the salient features of the invention as expressed in the appended claims.

In the drawings:

Fig. 1 is a view illustrating in side elevation the plug and socket forming the new coupler of the present invention, the socket part being illustrated mounted upon the cover plate of a conventional electrical outlet box;

Fig. 2 is a view showing the plug and socket or socketed receptacle joined together with the socketed receptacle being shown in section and illustrating the plug in the first of two positions which it is caused to assume in the operation of establishing the connection and in which position the complete electrical connections between all current conducting elements have not been established;

Fig. 3 is a sectional view on an enlarged scale, taken substantially on the line 3—3 of Fig. 2 in a plane transversely of the receptacle socket and plug;

Fig. 4 is a sectional view on an enlarged scale, corresponding to Fig. 3 but showing the plug rotated in the socket to its second position in which all current conductors are electrically connected;

Fig. 5 is a sectional view taken substantially on the plane of line 5—5 of Fig. 4 and showing the interior construction of the plug and the association of parts with contacts in the receptacle or socket;

Fig. 6 is a view in plan of one side of the socketed receptacle showing one of the terminals with which a current conductor is connected and showing the current carrying or hot plate which is embedded in the insulation of the receptacle, in dotted outline;

Fig. 7 is a view in perspective of the underside of a hot plate showing the circuit making and breaking unit carried thereby and which unit embodies a sealed envelope and two normally separated contacts therein;

Fig. 8 is a fragmentary detail section on an enlarged scale, taken substantially on the line 8—8 of Fig. 1.

Fig. 9 illustrates another form of construction for the circuit making and breaking unit wherein a spring element is housed within the envelope to assist in the separation of the encased contacts;

Fig. 10 shows another embodiment of the circuit making and breaking unit in which a spring is embedded in the flexible or resilient wall of the envelope.

Referring now more particularly to the drawings, there are shown the two principal or major parts of the coupler embodying the plug part, which is generally designated 10, and the socketed receptacle part which is generally designated 12 and which is formed to receive a portion of the plug part.

The receptacle 12 is illustrated as mounted upon the cover plate 14 of a conventional type of electrical outlet box which is shown in Fig. 1 in dotted outline and designated 16. However, while the receptacle 12 will hereinafter be described with particular relation to the manner in which it is joined to the cover plate 14, it is to be understood that the coupling is not necessarily limited to the mounting of the receptacle on a cover plate of an outlet box, as illustrated, but may be in the form of a molded terminal for a cable for effecting the electrical connection or coupling together of two cable ends, one of which carries the plug part 10 of the character shown.

The receptacle part comprises a molded body 18 of a suitable insulation material which may be vulcanized rubber, plastic, such as Bakelite or the like, or any other suitable material. The body is here shown as being sub-

stantially cubical although it will be obvious that the exterior physical form of the body is not material, but in this illustrated form the body has the opposite side faces 20 and 21, the right angularly related faces 22 and 23, and the back wall or face 24.

The forward face of the body, in the form here illustrated, is molded directly against the rear surface of the outlet box cover plate 14, such forward face of the receptacle being designated 25, and, as shown, a portion of the receptacle material is extended through the opening 26 in the receptacle box cover plate and is radially extended on the front face of the cover plate to form the locking collar 27.

The body 18 has formed therein through the front face 25 and concentric with the collar 27, the socket 28 which at its outer end is enlarged through a portion of its extent forming a first annular set-back 29 which joins a second annular set-back 30, of larger diameter and which constitutes the inner surface of the collar portion 27.

The opposite sides of faces 20 and 21 of the body 18 are formed in the molding of the body with shallow rectangular recesses 31 which are subsequently filled with the insulation material in the completion of the receptacle, as will hereinafter become apparent, and in this molding of the body there are also formed upon diametrically opposite sides of the socket 28 the pockets 32 which are of insufficient depth to merge with or intersect the wall of the socket 28. These pockets receive portions of the hereinafter described terminal units each of which is generally designated 33 and one of which is shown in perspective in Fig. 7.

The wall of the cylindrical socket 28 is formed in the molding of the insulation body with the diametrically opposite longitudinal guide grooves 34 which lie in a plane at right angles to the plane of the centers of the pockets 32. Each of these grooves is of a depth to have the bottom thereof flush with the first offset 29 and at its inner end each of the longitudinal grooves 34 joins one end of an approximately quarter-circular groove 35 extending in the circumferential direction of the socket or concentric with the axis of the socket, and each of these quarter-circular grooves 35 intersects the inner portion of a pocket 32 as is clearly shown in Figs. 3 and 4. As shown in these last mentioned figures, the quarter-circular grooves extend from their respective longitudinal grooves 34 in the same circumferential direction so that one does not connect with the other.

At the bottom or inner end of the socket 28 the insulation body has a metal piece in the form of a block 36 embedded therein and exposed on the face 24 of the insulation body and a reduced bore 37 extends from the bottom or inner end of the socket 28 to the block 36 and in line with this bore 37 the block 36 has a pit 38 therein for the purpose hereinafter set forth. This block 36 provides a grounding terminal with which a suitable ground wire can be connected by means of the screw 39 or in any other suitable manner.

The terminal units 33 which are fixed in and to the insulation body 18 at opposite sides thereof beneath the insulation covering faces 20 and 21, are of duplicate construction and, therefore, description of one applies to the other and the same reference numerals will be applied to both of the illustrated units.

Each unit 33 comprises a metal plate 40 formed to fit in the rectangular recess 31 and which plate, for facility in understanding the construction and operation of the invention, may be referred to as the hot plate, in view of the fact that either of the two plates shown may have the hot wire of the electrical system connected therewith.

Each plate 40 has an aperture 41 therethrough adjacent to each of its corners and at the center such plate has an aperture 42 in which is fixed the swaged over stud 43 carried by a contact button 44 which is secured

against the inner face of the plate 40. This contact or contact button 44 will be hereinafter referred to in the specification and claims as the hot contact, to facilitate distinguishing it from the about to be described coating contact button which is cold or does not have direct connection with the hot plate and the hot wire of the electrical conductors.

Molded to the inner face of the hot plate 40, that is, the face against which the hot contact 44 is positioned, is an elastic dome or envelope of insulation material 45 formed of an elastomer of suitable character, such as rubber, either natural or synthetic, plastic or the like. This dome or envelope 45, which is hermetically sealed to and against the inner face of the plate 40, carries a cold contact button 46 upon its inner side which is in opposed relation with the hot contact 44 and normally maintained spaced from the latter by the inherent tendency of the envelope dome to assume its normal shape.

The cold contact button 46 is electrically connected 20 through a neck extension 47 passing through the wall of the envelope, with an end of a resilient contact strip 48. As shown, the contact strip 48 curves laterally and downwardly across the side of the envelope 45 to a laterally extending portion 49 of the insulation envelope, to which 25 extension it is riveted or otherwise suitably secured, as indicated at 50.

The pockets 32 are suitably shaped in the molding of the insulation body to receive the contacts enclosing envelope 45 when the plate 40 is placed in position in 30 the recess 31 and when the unit is so placed, the inner end of the contact strip 48 which is attached to the cold contact button 46, will project into the adjacent quarter-circular groove 35. The units are placed in their respective recesses 31 so that the curving surface of the contact strip 48 will be adjacent to that end of the quarter-circular groove which joins with the longitudinal groove 34, the purpose of this arrangement being made clear hereinafter in connection with the description of the cooperating plug.

40 The insulation body 18 has molded therein adjacent to the corners of each of the recesses 31 a metal body or nut 51 for alignment with an aperture 41 of the adjacent plate 40 and the body 18 is also provided with a bore 52 leading from the plate aperture 41 to the 45 threaded center of the nut body 51 to permit the passage of the threaded shank 53 of a securing and terminal screw 54.

In the finished receptacle the insulation material will 50 be disposed over the outer side of the hot plates 40 and the securing and terminal screws 54 and attachment of a current conducting wire to one of the terminal screws 54 is effected by removing or cutting away a necessary amount of insulation over the terminal screw to bare the latter so that it can be removed and the 55 conductor wire attached in the conventional manner. Fig. 8 illustrates such a conductor wire which is designated 55 and which carries at its end a conventional eyed terminal 56 through which the screw 54 has its shank extended and when it is threaded up tightly in the nut 51 the eyed terminal 56 will be drawn into electrical 60 connection with the hot plate 40.

Referring now to the plug part of the connector, it will be seen upon reference particularly to Fig. 5, that this comprises an elongate body 57 of a suitable insulation material such as that described in connection with the receptacle body 18, and this body 57 has a forward end portion which is stepped down in the two annular shoulders 58 and 59 to meet the elongate cylindrical terminal portion 60.

70 The terminal portion 60 of the plug part is of a diameter to be received snugly in the circular socket 28 of the receptacle and when the inner end face 61 of the portion 60, which is squared with the axis of the plug, is against or in close proximity to the bottom of the socket 28, the annular portions 58 and 59 will be fitted

tightly in the respective set-backs 30 and 29 of the socket. This forms a water tight and gas tight joint between the plug part and the receptacle or socketed part.

The body 57 has molded therein the longitudinally extending conductor strips 62 with which are connected at their outer ends by rivets 63 or in any other suitable manner, the current conductor wires 64 forming a part of the insulation sheathed cable 65. The insulation sheath of the cable is joined with the outer end of the body 57 of the plug part preferably in the molding of the plug part so as to provide a continuous insulation protection over all of the embedded conductors.

The conductor strips 62 terminate short of the end face 61 of the terminal portion 60 in the radially outwardly extending contact heads 66. These heads which are diametrically opposite one another have sloping outer or radially directed faces 67 and they project a sufficient distance beyond the side of the terminal extension 60 to have sliding engagement in the longitudinal grooves 34 when the extension portion 60 is inserted into the socket 28. Also the heads 66 are spaced the proper distance from the portions 58 and 59 so that when these are firmly seated in the set-backs 30 and 29 in the manner stated, the heads will be in position to enter the quarter-circular grooves 35 when the plug body is rotated in the proper direction.

As will be readily seen upon reference to Figs. 3 and 4, when the plug is so inserted in the receptacle socket and is given clockwise rotation, the contact heads 66 will move through the adjacent quarter-circular grooves 34 and the sloping or inclined end faces 67 thereof will ride onto the curving surfaces of the contact strips 48, and force the cold contacts outwardly and into electrical engagement with the hot contacts 44 adjacent thereto. The resilient contact strip 48 and the flexed bodies of the resilient envelopes encasing the contacts will, upon reverse rotation of the plug to move the heads 66 back into the inner ends of the longitudinal grooves 34, react to separate the contacts 44 and 46 in the envelopes.

The cylindrical extension 60 of the plug body has extending longitudinally therein the ground contact rod 67a, which passes through and is maintained centrally between the conductor strips 62 by the end spacer 68 and the mid spacer 69. These spacers are formed of relatively hard plastic having impact resistance as contrasted with the body 57 of the plug proper which is somewhat resilient and which, as hereinbefore stated, is formed of an elastomer, preferably, neoprene. The forward end of the ground contact rod is joined to the metal ground contact tip 70 which projects from the portion 60 of the plug on the axial center thereof and is formed to enter the pit 38 in the ground connected body 36.

The rear end of the rod 67a is electrically connected by a tubular solderless butt connector 71 with the ground wire 72 which passes outwardly through the plug with the conductor wires 64 and is enclosed in the plug sheathing 65.

As hereinbefore stated, the coupler of the present invention is particularly well adapted to be used in areas where inflammable or explosive gases are apt to be found and in addition to such use in industrial plants, chemical laboratories and the like, the coupling is especially well adapted for use in mines where both explosive gases and moisture are nearly always present.

The coupling may be used for connecting together ends of multi-wire cables as well as for connecting an end of one multi-wire cable with wires leading into an outlet box, such as that shown in Fig. 1. Where employed for connecting multi-wire cable ends together, the receptacle body 18 may, as hereinbefore stated, be cast with all wires completely embedded in insulation in a manner similar to that in which the wires are shown sheathed and embedded in the outer end of the plug body 57.

The coupling when formed in the manner stated in the preceding paragraph, may then be safely used, not only in atmosphere containing explosive gases but in areas which are or may be wet most of the time, such as in mines or around ships and decks.

By the provision of the annular set-backs in the socket and the ribs or circular portions on the plug body, these parts can be telescoped together in a fluid and gas tight coupling which will prevent the entrance of moisture into the socket when the coupling is in use.

In the installation of the receptacle 12 in an outlet box it will be understood that while certain of the terminals are exposed within the box, the admission of moisture thereto may be prevented where the box is completely embedded in concrete or the like. In such case, even though the structure in which the outlet box is housed may be submerged, no water can enter the socket when the plug is connected therein.

While the invention has been illustrated and described as embodying a pair of terminal units in the receptacle body 18 for cooperation with a pair of contact heads connected with wires 64, it will be readily appreciated that the invention may be incorporated in a coupler comprising two bodies 10 and 12 and carrying a single terminal unit and single contact head 66 for use in a series connected electrical system.

It will be readily apparent from the foregoing description that in the use of the present coupler when the reduced end portion 60 of the plug part is inserted into the cylindrical socket 28, the contact head 66 will enter and ride along in the longitudinal grooves 34 until they reach the inner ends of the grooves, at which time no circuit connection will be made but the ground contact 70 at the forward end of the plug will have entered the pit or recess 38 in the body 35 which would have been previously connected to a ground wire. After the axial extension of the plug into the socket in the manner stated, the outer end of the socket will be tightly closed against the entrance of moisture by the frictional engagement of the portions 58 and 59 in the offset portions 30 and 29, respectively, as hereinbefore stated, and the plug may then be turned or rotated a quarter turn so as to ride the sloping end face 67 of the contact head 66 onto the metal conductors 48. Since these conductors project a substantial distance into the quarter-circular grooves 35, they will be flexed outwardly, deforming the elastic envelope 45 in the manner illustrated in Fig. 4 and forcing the cold contacts into electrical engagement with the hot contacts 44. Thus it will be seen that the socket will be completely closed before there is any metal to metal contact between parts carried by the plug and parts carried by the terminal units. At the same time, since the contacts of the terminal units are completely enveloped in a gas and liquid tight enclosure, any sparking which may occur either in the closing of the contacts or in the separation thereof will be completely shut off from the outside atmosphere.

In the structure illustrated in Figs. 3 to 5 and 7, of the capsule enclosed or enveloped contacts, a resilient striker strip 48 is shown, which has been described as being resilient to function, in addition to its stated function of providing a wiper surface over which the contact heads ride, as a spring to coat with the resilient envelope in separating the contacts. Other resilient means may be employed, either independently or in association with the resilient strip 48, as illustrated in Figs. 9 and 10. Such other spring means may be designed to bear against the inner surface of the envelope wall to urge the return of the envelope to its normal condition after being compressed, or such spring may be molded in the resilient wall of the envelope. When placed within the envelope or molded in the wall thereof, the spring may be of the coil type or any other suitable type or form which will accomplish the desired purpose or perform the desired function.

In addition to the foregoing, such coil spring or other type spring enclosed in the envelope or capsule or molded therein, may be used along with the disclosed striker strip 48.

In Fig. 9, for example, there is shown a diaphragm or envelope 45a corresponding to that shown in preceding figures and hermetically sealed around its perimeter to a supporting plate 40a which may be of metal, if the unit is to be installed in the manner illustrated in Figs. 3 and 4, or it may be of rigid insulation material of a suitable character so that the unit may be fully embedded in a carrying body of insulation and electrical connection made with the hot contact 44a by a conductor 40b, as illustrated.

The cold contact in this unit is designated 46a and the enclosed spring means above referred to is designated 100 and is in the form of a one or two turn helix which bears at one end against the top of the plate 40a while at its other end it encircles and is free from engagement with the contact 46a and bears against the top of the envelope.

In Fig. 10 there is illustrated a spring means within the envelope 45b which spring means is designated 101 and as shown is fully embedded in the body of the insulation envelope so that it is completely encased or covered by the insulation material. In this unit the other parts are shown as being the same as in Fig. 9, such other parts here comprising the base 40c against one side of which the periphery of the envelope is sealed, while the hot and cold contacts are here respectively designated 44b and 46b and the current conductor connected with the hot contact is designated 40d.

In the preceding description the envelope 45 enclosing the spaced contacts 44 and 46 has been described as placed in a preformed or premolded recess in the insulation body 12.

The modified embodiments of Figs. 9 and 10 may also be so installed. However, in the molding of the insulation bodies, these units could be embedded in the insulation material, in the body wall, coincidentally with the molding of the body. Of course, it will be obvious, or understood, that in such operation of molding the units a substantial portion of the top of the diaphragm or capsule will be made to project into the socket so that it can be contacted either against the striker strip or against the exposed outer end portion of the cold contact by the terminal head 66 of the plug when the latter is placed in operative position in the socket.

Also in addition to the foregoing, the diaphragm or capsule enclosing the spaced contacts could be incorporated in the structure of the portion of the plug body which extends into the socket in a suitable manner so that either the striker strip or the exposed outer portion of the cold contact would project beyond the side of the reduced portion of the plug for engagement against a terminal exposed in the socket. With this arrangement, it will be seen that with the units embedded in the extended portion of the plug so that the said parts of the capsule or envelope are exposed or extended beyond the side of the plug, when the reduced portion of the plug is inserted into the receptacle the striker strip, or exposed part of the cold contact, will ride over a cooperating contact in the receptacle and the capsule or diaphragm will be compressed against the resistance of the spring striker strip and the resistance of the resilient capsule wall or, in the case of the embodiment shown in Figs. 9 and 10, the capsule will be compressed against the resistance of the spring housed therein or embedded in the capsule wall.

In addition to the foregoing arrangement, a capsule or envelope might be placed in any other desired or suitable location to be made effective for the closing of an electric circuit by the application of another body thereagainst, which other body may be another electric current conductor or a body of non-conducting material,

such as a button designed to be manually pressed or pressed by a suitable force-applying element.

An example of another use of the capsule would be its placement in or upon the advancing end of the plug body to be compressed, for the closing of the contacts and completion of an electric circuit, when the plug is fully inserted into the receptacle, the completion of the electric circuit being effected after the exposed part of the current conducting portion of the cold contact has been electrically connected with a terminal in the bottom of the socket by the compression of the receptacle.

While in the modified embodiments shown in Figs. 9 and 10 a coil spring or helix has been illustrated and described, it will be obvious that the same desired results may be obtained by the use of various other forms of spring, either placed within the capsule or embedded in the wall thereof.

I claim:

1. An electric cable coupler comprising two bodies 20 of insulation, an electric current conductor secured to each body, one body having a cylindrical socket therein, the other body having a cylindrical portion extending therefrom and adapted to be axially introduced into said socket, said socket having a first groove in and extending 25 longitudinally of the wall thereof and joining at its inner end with an arcuate circumferentially directed second groove, an electric terminal unit embedded in said one body and embodying a first contact having a portion projecting into said second groove, said current conductor in the one body being electrically connected to a second contact in said unit adapted to be electrically joined to a part of said first contact, a terminal head carried by and projecting radially from said cylindrical portion of said other body and electrically connected to 30 the current conductor in said other body, said terminal head being adapted to ride in said grooves when said portion is axially introduced into the socket and then axially rotated and said terminal head engaging said first contact portion of the unit and effecting establishment of electrical connection between the current conductors of said bodies upon completion of said axial rotation of said cylindrical portion.

2. The invention according to claim 1, wherein the outer end portion of the socket and a part of said other 45 body encircling the cylindrical portion are formed to have interfitting fluid tight engagement when the cylindrical portion is substantially fully extended into the socket, forming a fluid tight joint closing and sealing the socket against entrance of liquids and gases.

3. The invention according to claim 1, wherein said first and second contact portions of said terminal unit are respectively cold contacts, means connected with the cold and hot contact and urging movement thereof away from the hot contact, and said means urging said contacts into electrical connection.

4. The invention according to claim 3, with means enveloping and forming a fluid and gas tight enclosure for the said electrically joined parts of said contacts.

5. The invention according to claim 3, with means 60 formed at least in part of an elastomer, enveloping and forming a fluid and gas tight enclosure for the electrically joined parts of said contacts, and said elastomer part carrying the cold contact and embodying a part of the first stated means.

6. The invention according to claim 1, wherein said terminal unit embodies a metal plate embedded in the said one body and having the current conductor electrically connected thereto, the said second contact being a hot contact joined to the plate, the said first contact being a cold contact, means supporting the cold contact in opposed relation with and insulated from the hot contact, said means yieldingly urging the cold contact away from the hot contact, and a current conductor element joined to the cold contact and being the said portion 75 projecting into the second groove.

7. The invention according to claim 6, wherein the said means supporting the cold contact comprises in part an elastomer dome bonded to said plate and enclosing the pair of hot and cold contacts.

8. The invention according to claim 1, with a terminal carried by said one body adapted to have a grounded conductor connected therewith, a grounding conductor passing through said cylindrical portion of the other body, and means for effecting electrical coupling of the last terminal and the grounding conductor coincidentally with the substantial completion of the axial movement of the said cylindrical portion into the socket.

9. The invention according to claim 6, wherein the said means supporting the cold contact comprises in part a dome-like cover over the hot contact and bonded to the metal plate and supporting the cold contact therein, said cover being formed of an elastomer, and said current conductor element comprising a flexible metal strip secured at one end to and insulated from the plate and having its other end engaging the outside top surface of said cover and electrically connected therethrough to the cold contact.

10. A coupler for electric current conductors comprising a first body of insulation having a socket therein, a second body of insulation having an elongate portion adapted for insertion in said socket and formed to tightly fit in and establish a gas and liquid tight seal with the wall of the socket, a pair of electric terminals in said socket adapted to have current conductors connected therewith, a pair of electric terminals carried by and exposed on the surface of said elongate portion, means for restricting said portion of the plug to a fixed path upon axial insertion to a limited extent into the socket whereby the plug terminals are stopped in spaced relation to the socket terminals, means facilitating movement of the plug terminals into electric connection with the socket terminals following insertion of the plug to said limited extent, and means for electrically connecting current conductors to the plug terminals.

11. A coupler for electric current conductors comprising a receptacle body of insulation having a plug socket therein, a plug body of insulation constituting having a terminal extension adapted for insertion into said socket, a pair of terminal units embedded in the insulation material on opposite sides of the receptacle body and each comprising a fixed contact and a movably supported contact, means for connecting electrical conductors to the fixed contacts, said socket having a pair of longitudinal grooves in the wall thereof each joining at its inner end with a substantially quarter-circular groove, each quarter-circular groove passing across and exposing a current conducting portion of a movably supported contact, current conductors extending longitudinally in said terminal extension of the plug, a terminal head for each conductor projecting laterally from said extension and adapted to move in said longitudinal and quarter-circular grooves upon axial insertion and rotational movement of the portion in the socket, and said terminal heads being arranged to ride onto said exposed current conducting portions of the movable contacts and move the latter into engagement with the fixed contacts.

12. The invention according to claim 11, wherein the said fixed and movable contacts are encased in a gas and liquid tight envelope.

13. The invention according to claim 11, wherein said socket at its outer end is defined by an annular offset and said plug has an annular shoulder adapted to fit tightly in said offset to form a gas and liquid tight joint.

14. The invention according to claim 11, in combination with an electric outlet box cover plate having an opening, said receptacle body being bonded to the inner side of said cover plate with the socket directed through and concentric with said opening, a portion of the receptacle body being extended through the plate opening

and formed to provide a locking collar engaging the outer face of the plate.

15. As an article of manufacture, an electrical terminal unit comprising as an integral structure a base plate adapted for connection of an electric current conductor thereto, a hollow substantially semi-spherical elastomer envelope hermetically sealed around its perimeter to a face of the base plate, a contact fixed in electrical connection to said face of the plate within said envelope, a second contact fixed to the inner wall of the envelope in radially spaced relation with the first contact, and a metallic element connected with the second contact and extending through the wall of the envelope and exposed upon the outer side thereof.

16. The invention according to claim 15, with a metallic strip secured at one end to said exposed metallic element and curving downwardly over the outer side of the envelope toward the plate and secured at its other end to and electrically insulated from the plate.

17. A coupler for electric current conductors comprising a first body of insulation material having a socket therein, a second body of insulation material having an elongate plug portion adapted for insertion into said socket, an electric current conductor having a terminal end embedded in the insulation material of the first body, an electric current conductor having a terminal end embedded in said plug portion of the second body, at least two cooperating electric current conducting parts carried by the insulation bodies and exposed at least in part for cooperative association respectively in the socket and upon the outside of the plug portion, said parts being electrically connected to the electric current conductors in their respective insulation bodies, said parts being electrically joined when the plug portion is in operative position in the socket, and one of said two parts embodying in its structure a pair of electrically isolated contacts and a resilient means operatively connected therewith and urging electrical separation thereof, and said contacts being urged into electrical connection against the resistance of said resilient means by the plug portion when the latter is in said operative position in the socket.

18. The invention according to claim 17, wherein the said one of said two parts further embodies in its structure a closed hermetically sealed envelope of resilient material constituting at least a part of the said resilient means.

19. The invention according to claim 17, wherein the said resilient means comprises a resilient envelope enclosing the contacts and hermetically sealed against the entrance of fluids thereto, and a spring means connected with the envelope.

20. As an article of manufacture, an electrical terminal unit comprising as an integral structure a base body, a hollow substantially semi-spherical elastomer envelope hermetically sealed around its perimeter to the base body, a contact within the envelope and secured to said base body, means for connecting an electrical conductor to said contact, a second contact fixed to the inner wall of the envelope in radially spaced relation with the first contact and electrically isolated from the first contact by the envelope, and a metallic terminal element connected with the second contact and extending through and exposed on the outer side of the wall of the envelope.

21. The invention according to claim 20, with a spring means operatively attached to the envelope and normally urging electrical separation of said contacts.

22. The invention according to claim 20, with a spring member enclosed within the envelope and exerting pressure against a wall of the envelope and against the base body to resiliently resist the movement of said contacts together.

23. The invention according to claim 20, with a spring

11

means embedded in the elastomer wall of the envelope and resisting movement of said contacts together.
